UNITED STATES PATENT OFFICE.

JOHN W. BOUNDS AND THOMAS J. McDANIEL, OF KANNAPOLIS, NORTH CAROLINA.

SHUTTLE-CHECK.

1,251,744.

Specification of Letters Patent. Patented Jan. 1, 1918.

Application filed April 12, 1917. Serial No. 161,625.

To all whom it may concern:

Be it known that we, JOHN W. BOUNDS and THOMAS J. McDANIEL, citizens of the United States, residing at Kannapolis, in the county of Cabarrus, State of North Carolina, have invented a new and useful Shuttle-Check, of which the following is a specification.

The subject of this invention is a shuttle check intended for association with a picker stick to check its action.

The main object of the invention is to produce a shuttle check which will check the picker stick both ways.

Another object is to produce a shuttle check which may be mounted adjacent the pivot point of the picker stick, and engage the stick to check its motion.

Another object is to produce a shuttle check in which picker stick engaging shoes are held by adjustable friction means.

Still another object is to produce a simple and efficient shuttle check.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

One practical embodiment of the invention is shown in the accompanying drawings, wherein:

Figure 1 is a side elevation of a shuttle check constructed in accordance with our invention, the same shown applied to a picker stick.

Fig. 2 is a side elevation of the device showing the side opposite to that shown in Fig. 1.

Fig. 3 is a front elevation.

Fig. 4 is a horizontal section taken on the line 4—4 of Fig. 3.

Referring to the drawings by characters of reference:

R indicates the usual rock shaft, to which is secured the parallel P, with its laterally extending bracket B. A picker stick S is pivotally engaged at its lower end, and there is provided the usual lug strap L which is looped around the picker stick.

Secured to the bracket B by means of a screw bolt 1, or otherwise, is a bracket arm

2, which is arranged beside and extends longitudinally of the parallel. One end of the bracket arm 2 may be turned down at right angles thereto, as at 3, to prevent the arm 2 pivoting on the screw bolt 1. The other end of the arm 2 is bent upwardly and quarter-turned to provide the upstanding support 4.

A disk 5, formed with a diametrical groove 6, to which the support 4 is adapted, is provided with a central bore 7 adapted to align with an aperture formed in the support 4, when the support is seated in the groove. As will be seen most clearly in Fig. 4, the depth of the groove 6 is greater than the thickness of the support 4. A stud 8 passes through the bore 7 and the aperture of the support 4, and is provided at a median point with a rectangular collar 9 which is adapted to be seated within the groove 6 and engage the support 4. A nut 10 threaded to one end of the stud 8 serves to bind the disk 5 in place on the support 4.

A leather disk 11, is provided with a central aperture through which passes the other end of the stud 8. A disk 12, having a central bore 13, is also mounted on this end of the stud 8 so that the leather disk 11 is bound between the disk 5 and the disk 12. A U-shaped bar 14 is provided with an aperture 15 for the reception of the stud 8, and the bar is secured by screws 16, or otherwise, to the exposed face of the disk 12. Bar 14 has its ends twisted and bent to form outwardly extending shoes 17, adapted to embrace the picker stick and alternately contact an edge thereof. The shoes 17 may be faced with leather or other suitable material, not shown, an opening 18 being provided in each shoe for the purpose of binding the same in place.

A leaf spring 19 has its ends engaging the exposed face of the disk 12, one of the ends preferably resting between the arms of the U-bar 14, and is bent to arch across said face. The spring 19 is apertured to receive the stud 8, on which it is held by a nut 20, which is threaded on the stud, and which also serves to tension the spring.

In practice, the device is used in the following manner:—The check is assembled and secured in place, as hereinbefore set forth. When the picker stick is thrown forward to cast the shuttle from the shuttle box, the first violent motion, which is the real impulse driving the shuttle, is checked

to little or no extent because the shoes do not bind tightly against each edge of the stick. After this first impulse, the stick and shoe are in contact causing the disk 12 5 to turn and rub the face of the leather washer which is interposed between the stationary disk 5 and the disk 12. This produces friction, controlled by the tension of spring 19 and nut 20, and causes the picker 10 stick to be checked in its forward movement. A similar action takes place on the return of the picker stick.

This action will be readily understood by referring to Fig. 1 wherein the picker stick 15 5 is shown in its rearmost position and in contact with one shoe 17, the other shoe 17 being held spaced from and forwardly of the picker. As the picker stick travels forward it will be drawn from contact with the rear shoe 17 and will move a certain distance before coming in contact with the forward shoe 17.

When the picker stick meets the forward shoe it causes the disk 12 to make a partial 25 revolution, which produces friction, as heretofore explained, and also causes the rear shoe 17 to be drawn to position to contact the picker stick on the return thereof.

Having described our invention, what we 30 claim as new and desire to secure by Letters Patent, is;—

1. A shuttle check, comprising a bracket

arm formed with an upstanding end, a disk provided with a diametrical slot adapted to receive said end, means for securing the disk to the bracket, a stud forming a part of said securing means, a friction disk on the stud and engaging the first mentioned disk, another disk on the stud, picker-stick engaging shoes carried by said disk, and means for 35 forcing the said disk against the friction disk.

2. A shuttle check, comprising a bracket arm formed with an upstanding end, a disk provided with a diametrical slot adapted 40 to receive said end, a stud for clamping the disk to the arm, said stud provided with a longitudinal extension, a friction disk mounted on the extension of the stud and engaging the first mentioned disk, another 45 disk loose on the extension, picker-stick engaging shoes carried by said disk, a spring engaging the face of the said disk, and means for adjusting the tension of the spring to adjust the pressure of the last 50 mentioned disk on the friction disk.

In testimony that we claim the foregoing as our own, we have hereto affixed our signatures in the presence of two witnesses.

JOHN W. BOUNDS.

THOMAS J. McDANIEL.
